[57] CLAIM

The ornamental design for a folding knife, as shown and described.

DESCRIPTION

FIG. 1 is a perspective view of a folding knife showing my new design;

FIG. 2 is a frontal elevational view thereof;

FIG. 3 is a right side elevational view thereof, with a blade thereof extended;

FIG. 4 is a bottom plan view thereof; and,

FIG. 5 is a right side elevational view thereof, with the blade thereof retracted.

The broken line portions of the drawings are for illustrative purposes only and form no part of the claimed design.
